FOLDING WALL TABLE

Leslie W. Walters, Pierson, Iowa, assignor of one-half to Robert G. Clay, Pierson, Iowa

Application September 27, 1946, Serial No. 699,778

1 Claim. (Cl. 311—19)

1

This invention relates to a legless table that is designed to be attached to a wall or similar support which, when in use, will extend from the wall at right angles thereto, and when not in use, will rest flat against the wall in parallel relation therewith.

An object of the invention is to provide a table that is designed to be attached to a wall and is provided with latching means that will retain it in folded or non-use position or unfolded or use position.

Another object of the invention is to provide a table that is simple in construction, durable and efficient in use, and can be inexpensively manufactured for the purpose designed.

With the above and other objects and advantages in view, the invention consists of the novel details of construction, arrangement and combination of parts more fully hereinafter described, claimed and illustrated in the accompanying drawings in which:

Figure 1 is a front elevational view of an embodiment of the invention in folded position;

Figure 2 is a sectional view on the line 2—2 of Figure 1 with the unfolded position shown in dotted lines;

Figure 3 is an interior view of the supporting frame;

Figure 4 is a sectional view on the line 4—4 of Figure 3;

Figure 5 is a sectional view on the line 5—5 of Figure 3;

Figure 6 is a bottom plan view of the table and

Figure 7 is a sectional view similar to Figure 2 with the table in unfolded position and partly broken away.

Referring more in detail to the drawings, the reference numeral 10 designates the supporting frame for the table and comprises the rectangular base 11 having sides 12 which are provided with elongated slots 13 which extend from the top edge of the sides downward for a major portion thereof.

The base 11 is provided with spaced apertures 14 whereby the frame 10 is secured to a wall 15 or similar support by means of fasteners 16.

Secured to the sides inwardly of the slots 13 and to the inner face of the base 11 slightly above the transverse center line thereof is the bar 17 having keeper openings 18 adjacent each end thereof, the use of which will be later explained.

Mounted for sliding movement in the slots 13 is the slide 19 comprising the axles 20 on which is mounted the tubular member 21 having the apertured wing portions 22 which are secured to

the table top 23 adjacent the rear edge thereof on the bottom face thereof by fasteners 24.

The axle 20 is bent at right angles at 25 to form the sides 26 thereof which are provided with contact projections 27 at the top thereof and contact projections 28 at the bottom thereof which engage the bottom of the slot 13.

Secured to the projections 28 inwardly thereof in parallel relation to the axle 20 is the crossbar 29 and angular braces 30 are secured to the projections 27 inwardly thereof and to the crossbar 29 at 31, and the braces and crossbar maintain the sides in right angular relation to the axle in constant contact with the bottom of the slot 13.

15 Mounted on the bottom face of the top 23 in sliding relation therewith is the latch frame 32 which compresses the U-shaped member 33 having the curved latch dogs 34 at the ends thereof which curve under the member 21 to engage the keeper openings 18.

Secured to the ends of the member 33 inwardly of the dogs 34 is the crossbar 35 which is parallel to the base of the member 33, and the sides of the member 33 are slidably mounted on the bottom of the top 23 by the curved bracket 36 secured to the top by fasteners 37.

Extending longitudinally of the table, and slidably mounted thereon by curved brackets 38 secured to the top 23 by fasteners 39 is the U-shaped control member 40, the ends of which are secured to the bar 35 at 41, and to the frame 33 at 42, and the base of the member 40 forms the operating handle 43.

Secured to the top 23 on the bottom face thereof is the hinge portion 44 of the brace bar 45 which is secured by a hinge portion 46 at the opposite end thereof to the base 11, and the brace is of a sufficient length to support the top at right angles to the base when the top is in unfolded position as shown in Figure 7.

Secured to the top 23 adjacent the forward edge thereof intermediate the member 40 and inwardly of the handle 43 is the U-shaped bracket 47 which slidably mounts the latch member 48 which is forced into latching position with the keeper 49 secured to the base 11 adjacent the bottom thereof by the coil spring 50 mounted thereon, a washer 51 on the latch member 48 engaging the spring at one end, and the bracket 47 engaging the spring at the opposite end.

The frame 32 has coiled springs 52 secured to the base of the member 33, and two eyes 53 secured to the bottom face top whereby the dogs 34 are retained in their respective keepers 18 until released therefrom by a pull on the handle 43.

In operation, the table top is pulled outwardly from the forward edge thereof after the latch 48 has been released, and the slide 19 will move downwardly in the slots 13 until the dogs 34 engage the keeper openings 18, and the top will then be latched in unfolded position ready for use. To fold the table, the handle 43 is pulled, releasing the dogs, and the rear end of the top is slid upwardly until the latch 48 engages the keeper 49 and the table is retained in folded position. The slide 19 engaging the bottom of the slot will prevent the table top from moving up at its forward end too far, and the latch dogs will prevent the table top from being lowered until released.

It is believed that from the foregoing description, the construction and operation of the invention will be apparent to those skilled in the art, and it is to be understood that minor changes in the details of construction, arrangement and combination of parts may be resorted to, provided they fall within the spirit of the invention and the scope of the appended claim.

Having thus described the invention, what is claimed as new and desired to be secured by Letters Patent is:

A device of the character described, comprising a supporting frame having a base and paral-

lel sides, vertical slots in said sides, a frame slideable in said slots, means on said frame for securing a table top thereon, means for supporting said top secured to said top and said supporting frame, and means on the bottom face of said top for latching said top at right angles to said supporting frame, and said last means comprising a U-shaped member, latch dogs on the end of said member, U-shaped controlling means secured to said U-shaped member at right angles thereto and spring means secured to said U-shaped member for forcing said latch dogs into a keeper means secured to said supporting frame.

LESLIE W. WALTERS.
